UNITED STATES PATENT OFFICE

FREDERICK W. BIELE, OF NEW YORK, N. Y.

DESIGN FOR BURIAL-CASKETS.

Specification forming part of Design No. 7,212, dated March 3, 1874; application filed October 15, 1873.
[Term of Patent 7 years.]

To all whom it may concern:

Be it known that I, FREDERICK W. BIELE, of New York city, in the State of New York, have invented a Design for a Casket, of which the following is a specification:

The design is represented in the accompanying figures.

Figure 1 is a horizontal section through the end portion alone. Fig. 2 is a side elevation, and Fig. 3 a plan view, of a casket having both ends according to my design.

Similar letters of reference indicate corresponding parts in all the figures.

A A represent portions of the sides, which are parallel and straight. B represents the center of the rounded end, and C D C D ogee curves at the corners, or the junctions of the ends with the sides. The portion C of the curve swells outward. The portion D of the curve swells inward. E is the molding.

The amounts of the curvatures may vary

somewhat without entirely defeating the effect of my design. The curves C and D together constitute what is known as an "ogee curve." The parallel sides are flaring in below upward, and the whole is pivoted around the bottom with a molding, as shown. The flaring sides, rounded ends, and ogee curves, as described and shown, form a very appropriate decoration, and produce a very fine effect.

What I claim is—

The design for a coffin, herein described and set forth.

In testimony whereof I have hereunto set my hand this 10th day of October, 1873, in the presence of two subscribing witnesses.

FREDERICK W. BIELE.

Witnesses:

W. C. DEY,
ARNOLD HÖRMANN.
